UNITED STATES PATENT OFFICE.

ANTONE LEAL, OF SELMA, CALIFORNIA.

WINDOW-FASTENER.

1,126,793.

Specification of Letters Patent.

Patented Feb. 2, 1915.

Application filed November 25, 1914. Serial No. 873,974.

To all whom it may concern:

Be it known that I, ANTONE LEAL, a citizen of the United States, residing at Selma, in the county of Fresno and State of California, have invented certain new and useful Improvements in Window-Fasteners, of which the following is a specification, reference being had to the accompanying drawings.

10 This invention relates to certain improvements in window fasteners and has relation more particularly to a device of this general character especially designed and adapted for use in connection with sliding sashes; 15 and an object of the invention is to provide a novel and improved fastener whereby the limit of movement of one of the sashes, preferably the upper sash, may be effectively controlled, especially when such sash has 20 been adjusted for the purpose of ventilation whereby unlawful entry is prevented.

Furthermore, it is an object of the invention to provide a novel and improved device of this general character which serves to 25 maintain both the upper and lower sashes in closed adjustment.

The invention consists in the details of construction and in the combination and arrangement of the several parts of my improved window fastener whereby certain important advantages are attained and the device is rendered simpler, less expensive and otherwise more convenient and advantageous for use, all as will be hereinafter more 35 fully set forth.

The novel features of the invention will be carefully defined in the appended claims.

In order that my invention may be the better understood, I will now proceed to describe the same with reference to the accompanying drawings, wherein—

Figure 1 is a fragmentary view in perspective of the window structure, showing a fastener constructed in accordance with an embodiment of my invention applied thereto; Fig. 2 is an enlarged view, partly in plan and partly in section of the fastener as herein embodied; Fig. 3 is a transverse sectional view taken through the fastener as herein embodied; and Fig. 4 is a view in perspective, detached, of one of the locking plates carried by the upper sash.

As disclosed in the accompanying drawings, F denotes a window frame having slidably mounted therein the sashes A and B, 55 said sashes being of conventional construction and being separated by the parting strips P, as is believed to be clearly apparent to those skilled in the art to which my present invention appertains. As herein embodied, one of the parting strips P at a point adjacent the meeting ends of the sashes, when in closed adjustment, is cut-away, as indicated at 1, and in such cut-away portion is adapted to be positioned my improved fastening device, the adjacent portion of the stile S being cut-away, as at 2, 60 in order that the intermediate portion 3 of my improved locking device may be disposed in substantial continuity with the 70 parting strip, for a purpose which is believed to be self-evident. As herein embodied, the intermediate portion 3 is carried by a base plate 4 adapted to be inserted within the cut-away or mortise portion 2 in 75 the stile S and is provided with the openings 5 through which suitable securing means are adapted to be directed. The intermediate portion 3 is provided with the elongated longitudinally disposed slot 6 disposed transversely thereof and pivotally engaged within such slot adjacent the opposite ends thereof are the wings 7 and 8 which are normally maintained in extended adjustment through the medium of the flat springs 9 secured to 80 the wings 7 and 8 adjacent their connected extremities, the outer or free extremities of such springs 9 overlapping and coacting one with the other in a manner which is believed to be self-evident. The inner wing 7 is 85 adapted to overlie the meeting rail 10 of the lower sash A and for which purpose said meeting rail 10 is provided with the metallic anti-wear plate 11 suitably secured thereto, while the outer wing 8 is adapted to coact 90 with the shoulders 12 afforded by the plates 14 embedded within the adjacent side rail 15 of the upper sash B, it being understood that such plates 14 are in a predetermined spaced relation, with the lowermost plate so posi- 100

tioned as to positively maintain said upper sash B in its closed adjustment.

In order that the outer wing 8 may be readily adjusted into a retracted or inoperative position, I provide the free extremity thereof with the laterally disposed angular finger 16 which may be readily and conveniently engaged by a digit of the hand and in order that such wing may be received with 10 in the slot 6, I provide a longitudinal edge of the portion 3 with a recess 17 adapted to accommodate the finger 16, as is believed to be clearly apparent.

While it is believed to be self-evident, it 15 may be well to state that the wings 7 and 8 are adapted, when fully retracted, to be disposed in substantial continuity with the complementary faces of the coacting parting strip P so that no obstruction will be offered 20 by said springs to the sashes A and B upon their vertical adjustment by an authorized person.

From the foregoing description, it is thought to be obvious that a window fastener constructed in accordance with my invention is of an extremely simple and comparatively inexpensive nature and is particularly well adapted for use by reason of the convenience and facility with which it may 30 be assembled, and it will also be obvious that my invention is susceptible of some change and modification without material departure from the principles and spirit thereof and for this reason I do not wish 35 to be understood as limiting myself to the precise arrangement and formation of the several parts herein shown in carrying out my invention in practice.

I claim:

40 1. In a window, the combination with relatively movable sashes and a parting strip interposed therebetween, of a member inserted within the parting strip and adapted to coact with said sashes, said member being provided with an elongated transversely disposed slot, wings pivotally connected to such member adjacent the opposite ends of the slot and adapted to coact with the sashes when projected for maintaining the same against movement, and means for normally maintaining said wings in a projected adjustment.

55 2. In a window, the combination with relatively movable sashes and a parting strip interposed therebetween, of a member inserted within the parting strip and adapted to coact with said sashes, said member being provided with an elongated transversely disposed slot, wings pivotally connected to such member adjacent the opposite ends of the slot and adapted to coact with the sashes when projected for maintaining the same against movement, and

coacting means carried by the wings for normally maintaining the same projected. 65

3. In a window, the combination with relatively movable sashes and a parting strip interposed therebetween, of a member inserted within the parting strip and adapted to coact with said sashes, said member being provided with an elongated transversely disposed slot, wings pivotally connected to such member adjacent the opposite ends of the slot and adapted to coact with the sashes when projected for maintaining the same against movement, and flat springs carried by the wings and in overlying relation for normally maintaining the wings in a projected adjustment. 75

4. In a window, the combination with 80 relatively movable sashes and a parting strip interposed therebetween, of a member inserted within the parting strip and adapted to coact with said sashes, said member being provided with an elongated transversely disposed slot, wings pivotally connected to such member adjacent the opposite ends of the slot and adapted to coact with the sashes when projected for maintaining the same against movement, and flat springs secured to the wings adjacent 90 their pivotal connection, the free extremities of said springs overlapping and coacting one with the other to maintain the wings normally projected. 95

5. A fastener of the character described comprising a member provided with an elongated transversely disposed slot, wings pivotally connected to such member adjacent the opposite ends of the slot, and means for normally maintaining the free extremities of such wings in a projected adjustment. 100

6. A fastener of the character described comprising a member provided with an elongated transversely disposed slot, wings pivotally connected to such member adjacent the opposite ends of the slot, and coacting means carried by the wings for normally maintaining the same projected. 110

7. A fastener of the character described comprising a member provided with an elongated transversely disposed slot, wings pivotally connected to such member adjacent the opposite ends of the slot, and coacting springs carried by the wings for normally maintaining the wings in a projected adjustment. 115

8. A fastener of the character described comprising a member provided with an elongated transversely disposed slot, wings pivotally connected to such member adjacent the opposite ends of the slot, and flat springs carried by the wings and in overlying relation for normally maintaining the wings in a projected adjustment. 120

9. A fastener of the character described comprising a member provided with an elongated transversely disposed slot, wings pivotally connected to such member adjacent the opposite ends of the slot, and flat springs secured to the wings adjacent their pivotal connection, the free extremities of said springs overlapping and coact-

ing one with the other to maintain the wings normally projected.

In testimony whereof I hereunto affix my signature in the presence of two witnesses.

ANTONE LEAL
